UNITED STATES PATENT OFFICE.

MERRITT F. POTTER, OF HINCKLEY, ILLINOIS.

LAMP-REFLECTOR.

SPECIFICATION forming part of Letters Patent No. 323,530, dated August 4, 1885.

Application filed August 18, 1883. (No model.)

To all whom it may concern:

Be it known that I, MERRITT F. POTTER, a citizen of the United States, residing at Hinckley, in the county of De Kalb and State of Illinois, have invented certain new and useful Improvements in Lamp-Reflectors; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to supports for lamp-reflectors, having for its object the ready adjustment of the reflector at any desired angle; and it consists of the construction, combination, and arrangement of parts, as will be hereinafter more fully set forth and claimed.

I use the ordinary concavo-convex silvered-glass reflector. Projecting from the center of the convex side is a metallic attachment, preferably about one inch in length and diameter.

Referring to the drawings, in which like letters refer to like parts, Figure 1 is a side elevation with my support in position for use. Fig. 2 is a detail front view showing my chimney guard or protector, which usually acts as an auxiliary support for the reflector, as will be hereinafter explained. Fig. 3 is a plan view of the lower portion of my support, embracing the collar of a lamp, which is partly broken away to show a groove therein. Fig. 4 is a transverse section of the chimney, showing the point of contact of the chimney and guard. Fig. 5 is a side elevation of the chimney and a vertical sectional view of the reflector, reflector-guard, hinge, joint, and thumb-screw, showing the reflector leaning against the chimney, the guard between them; and Fig. 6 is a plan view of the lamp, collar, and spring, the latter touching the former at three different points.

In carrying out my invention I use the support A, which is provided with elastic curved arms A', having points α adapted to slide in a groove in a lamp-collar. These curved arms are made tapering from their points to their support A, said points being bent abruptly inward toward the collar. By tapering the arms I add much to their durability and elas-

ticity, make the spring more flexible near the point, more equally distribute the strain along the spring, and much less at the center. It is difficult to make any ordinary clamp or spring 55 of sheet metal or wire keep its place upon the collar by frictional contact thereon, since the collars of nearly all lamps are made tapering from the bottom upward. A clasp which maintains its place on the collar by frictional 60 contact would not freely rotate around the collar, which is very desirable. I do not solely rely upon frictional contact to hold the arms A' in place, but make them so as to touch the collar in three places, (see Fig. 6,) to wit, 65 at their junction with the upright support A, and at each extremity where their terminal points are turned abruptly inward and are fitted in a groove in the collar, from which the weight of the reflector or any other ordinary force will be powerless to displace them, 70 while they are free to rotate around the burner. In case there is no groove in the collar a small one can be readily cut.

To the upper end of the support A is rigidly 75 secured a sleeve, B, in which the upper support slides, and is held by frictional contact, whereby the elevation of the reflector can be changed. A thumb-screw can be employed where a loose fit is desired. The upper end 80 of the support B' is hinged to and beneath the drum C, close to the reflector. The hinged joint is intended to be loose at all times, and the reflector inclines by its own weight (unless supported otherwise) toward the chimney until 85 its upper edge rests upon and is partially supported by the chimney. (See Fig. 5.) This is the position of the reflector in common use—viz, resting unbalanced on the hinged upright B' and leaning its upper edge against 90 the chimney for support. To render the support practical, and to protect the chimney and reflector from fracture by sudden contact, I attach to the upper edge thereof a wire shield, α' , which is about three inches long and will 95 keep the reflector and chimney from direct contact, leaving a small space between them for circulation of air, and while the reflector is in contact with the extremity of the shield the chimney touches it only in the center, thus 100 making the points of contact between the reflector and shield an inch or more apart, (see

Fig. 4,) thus avoiding all possibility of breaking either. Thus supported, the reflector is held more within the base of the lamp, and keeps its place against the chimney (the guard 5 intervening) much more steady than if rigidly attached to the support B².

The light may be thrown to a higher or lower point, or the reflector moved away from the chimney, by means of the thumb-screw C² 10 in the support B². By this arrangement the slightest turn of the thumb-screw forward will visibly move the top of the reflector backward, and a reverse motion will bring it forward by force of gravity alone. The advantage of 15 this construction over a set-screw, which holds by frictional contact, and requires to be loosened and tightened with every changing inclination of the reflector, must be obvious.

To protect the glass from the point of the 20 thumb-screw, I attach a friction-plate, a², suspended from the hinge-joint above.

Having thus fully described my invention, what I claim, and desire to secure by Letters Patent, is—

25 1. A divided support for lamp-reflectors, one part thereof hinged to the reflector, and having a thumb-screw, and the other part joined to it by a sleeve at its upper end, the lower end thereof adapted to be secured to the 30 collar of the lamp, in the manner set forth.

2. The guard a², attached to a lamp-reflector and adapted to support it by bearing against the side of the chimney, a portion of the guard being at right angles to the longitudinal axis 35 of the chimney, as and for the purpose set forth.

3. The protection-plate a², arranged between the end of the thumb-screw and the reflector, as and for the purpose set forth.

4. The curved spring-arms A', having their 40 terminal points bent inwardly, in combination with the collar of a lamp having a groove, as set forth.

5. In combination with a lamp and lamp-reflector support, the tapering spring-arms A', as and for the purpose set forth. 45

6. The curved, elastic, and tapering spring-arms A' of a lamp-reflector support, adapted to be combined with the guide-groove of a lamp-collar, and having but three points of contact therewith—to wit, at the center and 50 at each extremity thereof—whereby friction between the spring and collar is reduced, as and for the purpose described.

7. The combination of the reflector-support B², having the fixed nut and screw C² working 55 through the same, with the reflector hinged to the support and bearing against the screw, but unattached thereto, substantially as described.

8. The combination of the reflector, the 60 hinged support B², the thumb-screw C², the chimney and reflector guard, whereby when the thumb-screw is turned back and wholly withdrawn from contact with the reflector the latter will move toward the chimney until the 65 reflector-guard comes in contact with the chimney, as herein set forth.

In testimony whereof I affix my signature in presence of two witnesses.

MERRITT F. POTTER.
